UNITED STATES PATENT OFFICE

157,075

COLLAPSIBLE STAND

Abner A. Naulin, Wauwatosa, Wis., assignor to Aim, Inc., Milwaukee, Wis., a corporation of Wisconsin

Application April 16, 1947, Serial No. 138,431

Term of patent 14 years

(Cl. D33—19)

To all whom it may concern:

Be it known that I, Abner A. Naulin, a citizen of the United States of America, residing at Wauwatosa, in the county of Milwaukee and State of Wisconsin, have invented a new, original, and ornamental Design for a Collapsible Stand, of which the following is a specification, reference being had to the accompanying drawing, forming part thereof.

The figure is a perspective view showing a collapsible stand embodying my design.

The side and the back of the stand (not shown) are identical as those illustrated.

I claim:

The ornamental design for a collapsible stand, as shown and described.

ABNER A. NAULIN.
